US00D633918S

(12) **United States Design Patent**
Vance et al.(10) **Patent No.:** **US D633,918 S**
(45) **Date of Patent:** ** *Mar. 8, 2011(54) **PORTION OF A DISPLAY SCREEN WITH A USER INTERFACE**

(75) Inventors: **Michael Steffen Vance**, Kenmore, WA (US); **Jasdeep Singh Chugh**, Renton, WA (US); **Feridoon Malekzadeh**, Seattle, WA (US); **Valerie Lynn Goulart**, Seattle, WA (US); **Jupiter MacLeod Barton**, Seattle, WA (US); **Jared T. Benson**, Pleasant Hill, CA (US); **Christian Robertson**, Concord, CA (US); **Shilpa R. Shah**, Oakland, CA (US); **Gabriel J. White**, San Francisco, CA (US); **Gordon Kar Kee Kam**, Seattle, WA (US)

(73) Assignee: **T-Mobile USA, Inc.**, Bellevue, WA (US)

(*) Notice: This patent is subject to a terminal disclaimer.

(**) Term: **14 Years**(21) Appl. No.: **29/334,505**(22) Filed: **Mar. 27, 2009**(51) LOC (9) Cl. .... **32-00**(52) U.S. Cl. **D14/486**

Primary Examiner — Cathron C Brooks*Assistant Examiner* — Deanna Fluegeman(74) *Attorney, Agent, or Firm* — Knobbe Martens Olson & Bear LLP(57) **CLAIM**

The ornamental design for a portion of a display screen with a user interface, as shown and described.

DESCRIPTION

The FIGURE is a front view of a portion of a display screen with a user interface showing the claimed design.

The portion of the display screen and the portions of the user interface illustrated in broken lines form no part of the claimed design.
